[57] **CLAIM**

The ornamental design for a combination telephone, facsimile and still picture television information communication apparatus for home or office use, as shown and described.

DESCRIPTION

FIG. 1 is a front elevational view of a combination telephone, facsimile and still picture television information communication apparatus for home or office use showing our new design;

FIG. 2 is a rear elevation view of the design;

FIG. 3 is a left side elevational view of the design;

FIG. 4 is a right side elevational view of the design;

FIG. 5 is a top plan view of the design;

FIG. 6 is a bottom plan view of the design; and,

FIG. 7 is a perspective view of the design showing the apparatus supported by its stand and the hand-set removed from the main body of the apparatus.

FIG. 3

FIG. 2

FIG. 1

FIG. 5

FIG. 6

FIG. 4

FIG. 7
